SONIC PUMP

William S. Inglis, Ridgewood, N. J., assignor to
Curtiss-Wright Corporation, a corporation of
Delaware

Application October 21, 1944, Serial No. 559,819

12 Claims. (Cl. 103—75)

1 The invention relates to a sonic pump of general application, wherever it is desired to transport fluids of any kind, and the invention specifically relates to pumping mechanism actuated by sending rapidly repeated wave impulses downwardly through one wave transmitting column of non-flowing liquid for elevating a fluid from one location to another upwardly through another column as from a deep well to the surface of the earth.

It has been known heretofore to transmit sonic wave impulses downwardly through an upwardly moving column of liquid to operate a sonic valve at the intake end of the conduit acting to lift the flowing column. It has also been known to impose wave impulses on such a sonic valve through a non-flowing column of liquid, such as oil, and which oil column is distinct and separated from the column of fluid being pumped.

The primary object of this invention is to provide an improved form of liquid elevating means of the sonic pump type, the improvement being particularly in its manner of actuating the valves thereof to effect the pumping operation by rapidly succeeding elastic waves of compression and rarefaction, commonly designated as audible, sonic or supersonic vibrations and hereinafter collectively referred to as sonic vibrations.

Briefly, the invention features the use of a piston type pump provided with one or more intake ports leading therethrough, each port normally closed by a check valve and which check valves are operated by the reciprocal action of the piston, in turn vibrated by the wave impulses produced in the non-flowing column of liquid by mechanism capable of vibrating at sonic frequency.

Various other objects and advantages of the invention will be in part obvious from a consideration of the method features in the disclosure and from an inspection of the accompanying drawing and in part will be more fully set forth in the following particular description of one method of practicing the invention, and the invention also consists in certain new and novel modifications of the preferred method and other features of construction and combination of parts hereinafter set forth and claimed.

In the accompanying drawing the figure is a

2 view in vertical axial section of a preferred embodiment of the invention.

In the drawing there is shown a pump housing 10 of cylindrical form outlined by a cylindrical wall 11 depending from a plate 12 provided with openings 13 extending therethrough and for this reason sometimes hereinafter referred to as a spider. The spider is provided centrally thereof with a bore 14 of cylindrical form constituting 10 a piston guideway. The spider is provided centrally thereof with an upstanding cylinder 15, the bore 16 of which is reduced intermediate its ends to form an annular stop ring 17. The portion of the bore 16 between the shoulder ring 17 and 15 the bottom wall 18 of the cylinder 15 forms a guideway 19 in which reciprocates an oscillator 20, the stem 21 of which is slidably mounted in the pressure chamber 23 formed between itself and the spider 12. This piston is integral 20 with the stem and thus forms in effect a single double-headed spool-like reciprocating member guided in its vertical movement in the guideway 14.

The piston 22 is provided with a plurality of 25 circumferentially spaced apart inlet ports 24, the inner ends of which are countersunk to provide conical valve seats 25. Normally resting on each of the seats 25 is a check valve 26 sometimes hereinafter referred to as a sonic valve and here- 30 in shown to be of spherical form. For the purpose of limiting the extent of movement of each of the valves off its seat, there is disclosed a restraining cage 27. This cage is of inverted U-form and has its legs 28 passed through and 35 secured to the pump piston 22.

It is the intent to locate the pump housing at the location from which the fluid is to be pumped, such as the bottom of a well, and reaching therefrom to the surface of the earth are two long pipes 40 29 and 30 in telescopic relation. The upper portion of the pump housing is snugly intruded into the lower end of the outer pipe 29 and fastened thereto by a driven fit or by other approved means. The inner pipe 30 is of materially reduced cross sectional area compared to the cross section of the outer pipe 29, and has its lower end intruded into the upper end of the cylinder 15 and abuts against the annular shoulder 31 formed by the stop ring 17.

The inner pipe 30 is filled with some suitable

fluid 32 capable of efficiently transmitting the wave impulses of sonic frequency, and it is herein suggested that a light form of oil has proven satisfactory in situations such as is herein contemplated. The column of oil in the inner pipe also fills the portion of the chamber above the oscillator 20 so that there is a solid column of oil between the top surface 33 of the oscillator and the plunger 34 of a sonic vibrator 35. This vibrator is of any conventional form and the showing herein is simply symbolic.

The bores 14 and 16 and the oscillator 20 and its stem 21 have sufficient length dimensions so as to defeat possibility of the oil in the column 32 flowing past the oscillator into the pressure chamber 23. As some oil creeps between the oscillator 20 and the walls of the guideway 19, the oscillator is lubricated and thus is free to be responsive to the high speed vibratory action herein featured. However, in order to insure non-leakage between the oil column and the column of fluid being pumped through the pipe 29 in all operative positions of the oscillator a Sylphon bellows 36 telescopes a boss 37 depending from the spider 12 and also telescopes a boss 38 formed on the upper side of the pump piston. An intake screen or well casing 39 is shown with the lower portion of the pump housing 10 intruded into the same.

In operation, and assuming that the pump has been primed at least to the extent of there being liquid in the pressure chamber 23 with the valves 26 in their normal seated position and with the oscillator slightly elevated from the position shown in the drawing, the device is then ready for action. The sonic vibrator 35 is set in motion and an impulse is sent downwardly through the oil column 32 to lower the piston 22. A small portion of the fluid to be elevated is caused to enter the intake ports 24, pass the alternately opening and closing valves 26, the fluid so admitted passes through the pressure chamber 23, and upwardly through the ports 13 and through the annular space formed between the inner and outer pipes to the point of discharge at the earth's surface, or elsewhere.

Described more in detail, it will be understood that on the initial downstroke of the vibrator plunger 34, a wave of condensation will be sent downwardly through the oil column 32 with the result that the oscillator is moved downwardly from its initial position. The downward movement of the oscillator will similarly lower the pump piston 22 into the body of fluid therebelow within the casing 39. This fluid reacts on the seated valves 26 to move them from their seated position into their elevated open position shown in the drawing. This movement causes some of the fluid below the piston to by-pass the valves and move into the pressure chamber. On the succeeding upward movement of the sonic vibrator piston, a wave of rarefaction will be created in the oil column which will react on the oscillator to elevate the same slightly from the position shown in the drawing. This elevating movement will cause the pump piston to be similarly elevated, and this, in turn, will cause the fluid in the compression chamber 23 to react on the valves 26 and thus to move them back into their initial seated position, thus intercepting the possibility of the liquid in the pressure chamber from retreating downwardly back through the inlet ports 24. This liquid in the pressure chamber is elevated by the raising of the pump piston, thus forcing a portion of the liquid in the pressure

chamber upwardly through the ports 13 and into the fluid conduit as indicated by the long arrows.

It will be understood that this alternate raising and lowering of the pump piston with its associated opening and closing of the valves will be repeated with each change of direction of the sonic vibrator piston.

By means of a device of this character, it is possible to effect an economic actuation of the sonic pump without loss of the actuating liquid in the oil column, and as this oil column is contained within the conduit for the pumped liquid, the whole device may be contained in a single well casing in the event that the device is used in well pumping. The disclosure features simplicity of parts, particularly in the movable parts which in effect have been reduced to a single unit and which unit may be readily replaced, when worn, with a new unit.

I claim:

1. In a sonic pump for elevating fluids from a lower to higher location, the combination of two pipes in telescopic relation, the space between the inner and outer pipes forming a fluid conduit for the fluid being pumped, a pump casing fitted into the lower end of the outer pipe, said pump casing including an apertured plate provided with a guiding opening extending axially therethrough and an upstanding cylinder into which the lower end of the inner pipe intrudes, a double-headed oscillator including a stem slidably mounted in the opening for reciprocating movement, having its upper head slidably mounted in the upstanding cylinder and having its lower head slidably fitted in the pump casing, said lower head provided with at least one inlet port and a valve normally closing the port, and the portion of the inner pipe above the oscillator adapted to contain a column of non-flowing fluid for transmitting therethrough waves of condensation and rarefaction of sonic frequency for reciprocating the oscillator and thus in raising and lowering the lower head to alternately cause the valve to open and close the inlet and means at the top of said column for imposing thereon waves of sonic frequency.

2. In a sonic pump, the combination of a closed tube adapted to contain a stationary column of liquid, an oscillator mounted for reciprocatory movement at the bottom of said column, means at the top of the liquid column for imposing waves of condensation and rarefaction of sonic frequency on the column of liquid to cause wave formations in the secondary column to vibrate the oscillator, a pump casing provided with a plunger mounted for reciprocatory movement and operatively connected to the oscillator to be oscillated thereby, said plunger provided with an inlet port, and having a valve seat at the upper end of the inlet port, a check valve normally closing the inlet port and means for limiting the movement of the valve off its seat.

3. A sonic pump including a pump casing, a plunger provided with an inlet port extending therethrough, means supporting said plunger for reciprocatory movement in the casing, a normally closed valve for alternately closing and opening the port, means providing a non-flowing column of liquid, means at the upper end of the column for imposing waves of alternate condensation and rarefaction on said column and means acted upon by said waves and connected to the plunger to oscillate the same and thus move the plunger relative to its valve and

to the material being pumped thereby to cause the valve to open as the plunger is lowered and to close as the plunger is elevated.

4. A sonic pump including means providing a stationary column of liquid, means at one end of the column for imposing thereon waves alternating of condensations and rarefactions, an oscillator at the opposite end of the column oscillated by said waves and acting at all times to close the lower end of said column, and a pump piston rigidly connected to the oscillator and oscillated thereby to effect a pumping action of sonic frequency.

5. A sonic pump including a pump housing having a depending cylindrical portion, a piston mounted for reciprocatory movement in the cylindrical portion, said piston provided with a passageway extending therethrough, a check valve normally closing the passageway, means forming a stationary column of liquid, a sonic vibrator operating on the column to impose thereon waves of alternate compression and rarefaction of sonic frequency, and means between the column and the piston for translating the waves action in the liquid to a pumping movement of the piston.

6. In a sonic pump, the combination of a pump housing, a member mounted for reciprocatory movement in the housing and capable of vibrating at sonic frequency, said member including a pump piston provided with a valve controlled passageway extending therethrough, means providing a column of lubricating liquid engaging said member and acting to lubricate said member, and means for imposing sonic vibrations on the column to act therethrough and cause said pump piston to function.

7. In a device of the class described, a combination of two pipes in telescopic relation, a pump casing closing the lower ends of both pipes, a column of non-flowing liquid in the inner pipe, the pump casing being provided with passageways for passing the liquid to be pumped into the space formed between the inner and outer pipes, a sonic valve normally closing the passageways and actuated by impulses sent through the liquid in the inner pipe for moving the valve off its seat and means for imposing waves of sonic frequency on the liquid in the inner pipe to actuate the valve.

8. In a device of the class described, the combination of two pipes in telescopic relation, a column of non-flowing liquid in the inner pipe, the space between the inner and outer pipes providing a passage for the liquid being pumped means for creating in said column waves of condensation and rarefaction, a plunger actuated by said wave impulses in the non-flowing liquid column for lifting a column of liquid upwardly through said passageway and a valve acting in synchronism with the frequency of said wave impulse to prevent reverse movement of the liquid downwardly past the plunger.

9. In a sonic pump construction, the combination of two pipes in telescopic relation, a valvular unit fitted in the lower end of the outer pipe and including a plate provided centrally thereof with an upstanding cylinder into which is intruded the lower end of the inner pipe and said plate provided at its perimeter with a depending wall forming a depending cylinder, said plate provided centrally thereof with a bore forming a guideway connecting the cylinders, a double headed oscillator having a head of relatively small diameter slidably mounted in the upstanding cylinder, a

head of relatively large diameter slidably mounted in the depending cylinder and a stem connecting the heads and slidably mounted in the bore forming guideway, the space formed within the depending cylinder and between the plate and large diameter head forming a pressure chamber and said plate provided with openings placing the pressure chamber at all times in open fluid communication with the space between the two pipes, said head of large diameter provided with at least one inlet port, a sonic valve normally closing said inlet port, the inner pipe and portion of the upstanding chamber above the head therein being filled with stationary column of liquid capable of transmitting therethrough to the oscillator alternating waves of compression and rarefaction at sonic frequency and means at the top of said liquid column capable of generating therein said waves of sonic frequency.

10. The structure defined in claim 9 in which means are provided for preventing possibility of leakage of said liquid past the oscillator into the fluid being pumped through the pressure chamber.

11. A pump unit for installation at the lower end of a pair of telescoped pipes, comprising a plate provided with an upstanding cylinder, a depending cylinder and a bore extending through the plate and connecting the cylinders, a single double headed oscillator having one head slidably mounted in the upper cylinder and the other head slidably mounted in the lower cylinder and having a stem connecting the heads and slidably mounted in the bore, a fixed column of liquid, the upper cylinder containing the lower end of said fixed column of liquid in which the upper head is located, means for generating wave movement in the column of oil to vibrate the oscillator and means encircling the stem for preventing oil leakage from the upper cylinder into the lower cylinder, and valve means in the lower oscillator head responsive to the vibration of said oscillator for admitting fluid to said lower cylinder.

12. In a sonic pump construction, the combination of two pipes in telescopic relation, a valvular unit fitted in the lower end of the outer pipe and including a plate provided centrally thereof with an upstanding cylinder into which is intruded the lower end of the inner pipe and said plate provided at its perimeter with a depending wall forming a depending cylinder, said plate provided centrally thereof with a bore forming a guideway connecting the cylinders, a double headed oscillator having a head of relatively small diameter slidably mounted in the upstanding cylinder, a

55 head of relatively large diameter slidably mounted in the depending cylinder and a stem connecting the heads and slidably mounted in the bore forming guideway, the space within the depending cylinder and between the plate and large diameter head forming a pressure chamber and said plate provided with openings placing the pressure chamber at all times in open fluid communication with the space between the two pipes, said head of large diameter provided with at least one inlet port, a sonic valve normally closing said inlet port, the inner pipe and portion of the upstanding chamber above the head therein being filled with stationary column of liquid capable of transmitting therethrough to the oscillator alternating waves of compression and rarefaction at sonic frequency, means associated with said liquid column for generating therein said waves of sonic frequency, and means comprising a Sylphon bellows having one end fixed to the plate and the other end fixed to and movable with the head of

60 70 75

large diameter for preventing the leakage of said liquid past the oscillator into the fluid being pumped through the pressure chamber.
